DESIGN FOR A TOASTER

Charles I. Epstein, New York, N. Y., assignor to Toaster Corporation of America, New York,
N. Y., a corporation of New York

Application September 12, 1947, Serial No. 141,346

Term of patent 3½ years

(Cl. D81—10)

To all whom it may concern:

Be it known that I, Charles I. Epstein, a citizen of the United States, and a resident of New York city, county and State of New York, have invented a new, original, and ornamental Design for a Toaster, of which the following is a specification, reference being had to the accompanying drawing, forming part thereof.

Figure 1 is a perspective view showing the top, one side, and one end of a toaster embodying my new design;

Figure 2 is a perspective view showing the top, other side, and other end thereof with the tray element removed from the toaster; and

The heavy black lines on the base and on the opposite ends of the toaster are intended to represent contrasting colored areas.

I claim:

The ornamental design for a toaster, substantially as shown and described.

CHARLES I. EPSTEIN.
